DESIGN FOR A BROOM COVER FOR DUSTING PURPOSES

Eva H. Pratt, Wichita, Kans.

Application July 30, 1938, Serial No. 78,970

Term of patent 7 years

To all whom it may concern:

Be it known that I, Eva H. Pratt, a citizen of the United States, residing at Wichita, in the county of Sedgwick and State of Kansas, have invented a new, original, and ornamental Design for a Broom Cover For Dusting Purposes, of which the following is a specification, reference being had to the accompanying drawing, forming part thereof.

Fig. 2 is a rear view of the same;
Fig. 3 is an opened front view;
Fig. 4 is an edge view;
Fig. 5 is an opened end view.

I claim:

The ornamental design for a broom cover for dusting purposes, as shown.

EVA H. PRATT.
